UNITED STATES PATENT OFFICE

2,641,178

HOSIERY MARKING MACHINE

Gustav C. Wendt and Peter C. Wendt, Jr., Boonton, N. J., assignors to Pohatcong Hosiery Mills, Inc., a corporation of New Jersey

Application November 3, 1950, Serial No. 193,938

5 Claims. (Cl. 101--9)

1

The present invention relates to an apparatus for marking fabrics made of synthetic yarn by heat stretching loops or stitches in said fabrics. The apparatus is particularly useful in connection with nylon fabrics and especially with nylon hosiery to carry out the method disclosed in U. S. Patent #2,424,124 issued July 15, 1947. In accordance with this method, pointed heated needles arranged in accordance with a predetermined pattern are made to penetrate the fabric. These heated needles are thick enough to stretch the loops or stitches of the fabric penetrated and when these loops are set in stretched condition, they form an easily visible permanent design indicative of the gauge, denier or other characteristic of the fabric.

The present invention has for some of its objects the provision of an apparatus which is compact and occupies a minimum of floor space, which is easy and convenient to operate, which permits high rate of production, which produces designs with neatness, accuracy and uniformity, which permits the designs to be formed selectively either in color or without color without discoloring the fabric around the region of the design, which is safe and proof against the possibility of injury to the fabric, as for example by overheating, which is automatic in its control of the temperature to which the fabric is subjected during heat stretching operations and in the length of each fabric penetrating and heat stretching cycle, and which lends itself easily to adjustment in the degree of heat and period of each fabric penetrating cycle.

In the apparatus of the present invention, a series of needles heated and thermostatically controlled are made to penetrate the fabric to be marked. As one feature, means are provided under manual control for initiating each fabric penetrating cycle of the needles, and timer means are provided for automatically determining the length of the cycle and for withdrawing the needles from the fabric at the end of each cycle, as determined by the setting of said timer means.

As another feature, the stretched fabric loops are colored through a dye ribbon threaded through the apparatus and across the path of movement of the fabric penetrating needles, so as to be punctured by said needles in their movement towards the fabric to be penetratively marked. The dye from the ribbon is picked up by the puncturing needles and transferred to the loops of the fabric penetrated by said needles. This ribbon comes from a supply supported on the apparatus in a manner to permit it to be fed

2

across said path in successive steps so that a fresh ribbon section is presented to the needles prior to each fabric penetrating operation.

As a further feature, a protective ribbon for preventing direct contact between the dye ribbon and the fabric being penetrated is employed. This protective ribbon, intervening between the dye ribbon and the fabric, comes from a supply so supported on the apparatus as to permit the two ribbons to be fed together across the path of movement of the needles.

Various other objects, features and advantages of the present invention will be apparent from the following particular description and from an inspection of the accompanying drawings, in which:

Fig. 1 is a perspective of an apparatus in operation embodying the present invention and adapted to penetratively form an identifying design in fabric made of heat stretchable synthetic yarn;

Fig. 2 is a perspective of a stocking made of nylon or other heat stretchable synthetic yarn penetratively marked by the apparatus of the present invention;

Fig. 3 is a top plan view of the apparatus but with the supporting table and the cover removed;

Fig. 4 is a section of the upper part of the apparatus taken approximately along the lines 4--4 of Fig. 3;

Fig. 5 is an enlarged section of the upper part of the apparatus taken approximately along the lines 5--5 of Fig. 4;

Fig. 6 is a top plan view of the female die portion of the apparatus taken along the lines 6--6 of Fig. 5;

Fig. 7 is a perspective of the presser foot plate;

Fig. 8 is a section of the apparatus taken approximately along the lines 8--8 of Fig. 5 and showing the stretching needles in raised inactive position prior to the initiation of the fabric penetrating cycle;

Fig. 9 is a section of the apparatus taken approximately along the lines 9--9 of Figs. 5 and 8;

Fig. 10 is a side view of the solenoid controlled latch device for automatically raising the stretching needles at the end of a set fabric penetrating cycle as determined by a timer and shown while said needles are raised in inactive position and before the cycle has been initiated;

Fig. 11 is a side view of the latch device indicated in Fig. 10, but shown at the instant the needles have been lowered into fabric penetrating lower limiting position by operation of the manual control;

Fig. 12 is a side view of the latch device indi-

cated in Fig. 11, but shown at the instant the manual control is released and before the end of the fabric penetrating cycle;

Fig. 13 is a perspective of a catch or detent piece forming part of the latch device shown in Figs. 10, 11 and 12;

Fig. 14 is a rear view of the timer unit employed in the apparatus to terminate automatically the fabric penetrating cycle in accordance with the setting of said unit;

Fig. 15 is a side elevation of the timer unit shown with part of a frame plate removed and taken approximately along the lines 15—15 of Fig. 14;

Fig. 16 is a longitudinal section of the columnar supporting structure for the apparatus;

Fig. 17 is a detail bottom view of the base of the apparatus taken approximately along the lines 17—17 of Fig. 16; and

Fig. 18 is a wiring diagram for the apparatus.

Referring to the drawings and especially to Fig. 1, the apparatus comprises a frame structure made up in general of a base 10, a post 11 on said base and a hollow arm 12 at the upper end of said base housing part of the operating mechanism. Secured to the post 11 is a bed-plate 13 carrying a female die 14 (Fig. 5) for a bank of fabric penetrating needles 15. A head 16 carrying the needles 15 is mounted at the outer end of the arm 12 for reciprocation up and down with respect to said bed-plate. A table 17 (Fig. 1) may be provided to support the articles, such as the hosiery A, to be penetratively marked.

More specifically, the frame base 10 is of hollow construction as shown in Figs. 16 and 17 to house part of the operating mechanism and the post 11 comprises a hollow cylindrical pillar 18 (Figs. 1, 4 and 16) seated on said base, a short hollow column 20 of rectangular cross-section seated on said pillar and a bolt 21 rigidly securing said base, pillar and column together. The bed-plate 13 is secured to the column 20 by studs 22 (Fig. 4).

The arm 12 consists of a bracket 24 (Figs. 3 and 4) with a floor section 25 secured to the column 20 by studs 26 and a cover 27 seated on said floor section and removably secured to the bracket by means of a screw 28 which passes through the top wall of said cover and which is threaded into the upper end of an upright 29 extending from said floor section.

The needle carrying head 16 comprises a housing 30 (Figs. 1, 3, 4, 5, 8 and 9) for an electric heater 31 and carries a thermometer 32 indicating the temperature of said heater as well as a thermostat 33 for said heater seated thereon. The needles 15 of metal are secured in any suitable manner, as for example by press-fitting, to a rectangular metal plate 34, which in turn is fixedly mounted by screws 35 on a larger rectangular metal mounting plate 36 secured to the underside of the housing 30 by screws 37 and projecting on all sides beyond the corresponding sides of said housing for the purpose later to be described. Seated loosely on the plate 36 inside of the housing 30 is the heater unit 31 which may be of any suitable construction and which, in the specific construction shown, comprises a resistance strip inside a metal casing 38 carrying a pair of terminals 40 for the strip. The heat of the strip is conducted to the casing 38, the plate 36 and the needle plate 34 and then to the needles 15 themselves.

Mounted on the plate 36 is a presser foot 45 (Figs. 4, 5, 7 and 8) comprising an outer rec-

tangular metal plate 46 secured by screws 47 to an inner rectangular plate 48 made of fiber or other suitable insulating material. The outer plate 46 is provided with holes 50 in alignment with the needles 15 and of size to permit these needles to pass freely but snugly therethrough when the head 16 is lowered for fabric penetrating operation.

The presser foot 45 is yieldably mounted for movement towards and away from the mounting plate 36 and for that purpose four upright plungers in the form of studs 52 pass loosely through the respective corners of said plate and are threaded at their lower ends to the fiber plate 48. The heads 53 of these studs 52 seat on the end sections of the plate 36 projecting beyond the ends of the housing 30 and serve as stops to limit the downward movement of the presser foot with respect to the plate 36.

Means for yieldably forcing the presser foot 45 downward comprise a pair of parallel leaf springs 55 (Figs. 5, 8 and 9) secured to the projecting front and rear sections of the plate 36 by means of clamps 56 and screws 57 and having offset ends 58 engaging the stud heads 53. Each of these leaf springs 55 may comprise two thin superposed layers and their action is to hold the presser foot 45 yieldably down.

To permit the needles 15 to descend as far as possible with respect to the presser foot 45 in its fabric penetrating operation, the fiber plate 48 (Fig. 5) has a rectangular opening 61 corresponding in shape to the outline of the needle carrier plate 34 but slightly larger, to receive said plate 34 during this operation.

Since the metal plate 46 of the presser foot 45 is insulated from the studs 52 through the fiber plate 48 to which they are connected, this metal plate does not become heated by conduction from the heater unit 31.

The bed-plate 13 carries the female die 14 for the needles 15. For that purpose, the bed-plate 13 is formed with an opening 70 (Figs. 5, 6 and 8) defining a seat 71 for the female die 14. This female die is in the form of a plate and has a series of holes 73 in registry with the holes 50 in the presser foot 45. The die plate 14 is removably secured in place in the bed-plate 13 by means of screws 74 passing through said plate and said bed-plate and held tight in position by knurled thumb nuts 75 accessible from the underside of the bed-plate.

The needles 15, the holes 50 in the presser foot plate 46 and the holes 73 in the female die plate 14 are arranged in a pattern according to the identifying design to be applied to the stockings. The design may be in the form of a letter, number, word, pictorial illustration or other insignia. In the specific form shown in Fig. 2, the applied design consists of the letter "N" and the number "51," the latter indicating the gauge of the nylon threads.

It should be noted that the presser foot 45, the needles 15, the plates 34 and 36 associated therewith and the spring means 55 acting on said presser foot form a needle unit which may be removed as such from the housing 30 by removing the studs 37 and which may be replaced by a needle unit of a different fabric marking design. The female die plate 14 can be also easily replaced by one corresponding in design to that of the needle unit.

The thermometer 32 for the heater 31 comprises a pointer 80 (Figs. 1, 5 and 8) on the front wall of the housing 30 movable over a scale 81. The

thermostat 33 (Figs. 5 and 9) for this heater 31 may be of any suitable well known construction and has a pair of terminals 82 and an adjusting screw 83 accessible from the outside of the housing 30 through a hole 84 (Figs. 1 and 9) in the front wall of said housing. By turning this screw 83, the thermostat 33 may be set to maintain the temperature of the needles 15 to any desired point which may, for example, be the setting temperature of nylon, in case the fabric being marked is nylon. The temperature responsive element of this thermostat 33 may be in contact with the metal casing 38 of the strip heater 31.

The needle carrying head 16 is guided for sliding movement up and down. For that purpose, there is seated on and secured to the column 29 by screws 26 (Figs. 3 and 4) the bracket 24, the front end of which has an upward extension 92 (Figs. 3, 4, 5 and 8) with side flanges 93 to form a guide frame. Removably secured to the front face of this guide frame 92 by means of studs 94 is a pair of spaced guide strips 95 with V-shaped runways for a slide 97. This slide 97 is affixed to the head 16 by means of a plate 100 (Figs. 5 and 8) secured to said slide by long screws 101. The plate 100 in turn is attached by screws 102 to a block 103 which is affixed to the top wall of the housing 30 by screws 104. The block 103 is of insulating material to prevent the heat from the heater unit 31 being conducted to the frame arm 12 and to the operating structure therein. An electric connection 105, shown as a plug for the heater 31, is seated on and secured to the plate 100 and is adapted to be detachably connected to the power lines through an electric connection 106 (Fig. 18) shown as a socket member.

For manually depressing the slide 97, the base 10 carries a bracket 110 (Figs. 16 and 17) to which is pivoted a treadle 111 extending to the outside of said base and terminating in a foot piece 112. Pivotedly connected to this treadle 111 is the lower end of an upright rod link 113, passing through the post 11 and pivotedly connected at its upper end at 114 to a lever 115. This link 113 has a bumper stop 116 connected to its lower end for engaging the top wall 117 of the base 10 when the foot pressure is removed from the treadle 111 and for thereby limiting upward releasing movement of the link 113 with cushioning effect.

The lever 115 is pivotedly secured at its rear end at 118 (Figs. 3, 4 and 16) to an upward rear extension 119 of the bracket 24, passes through a slot in the upright 29, so as to be guided thereby in its angular movement, extends near its forward end through an elongated slot 120 (Figs. 3, 4 and 8) in the guide frame 92 and passes at its forward end snugly through a hole 121 in the slide 97 to form a connection between said lever and said slide. This connection permits limited angular movement of the lever 115 with respect to the slide 97, as said slide is moved up and down through the angular movement of said lever about its pivotal support at 118.

A coil spring 124 (Figs. 4 and 16) on the link 113, seating on the bracket 24 and bearing against a collar 125 on said link, urges the lever 115 upwardly and thereby normally maintains the head 16 carrying the needles 15 in raised inactive position.

When the foot treadle 111 is depressed, the head 16 is lowered and the needles 15 are depressed through the fabric on the bed-plate 13 to initiate the heat stretching cycle. The treadle 111 is released when foot pressure is removed therefrom, but a latch device holds the head 16

in depressed position against the action of the spring 124 for a period of time determined by the setting of the timer 130 (Figs. 3, 4, 14 and 15). The latch device comprises a movable piece 131 (Figs. 4, 8, 10, 11 and 12) pivotally suspended from a lug 133 on the rear side of the guide frame 92 by a pivot pin 134 and pivotally secured to the plunger 135 of a solenoid 136. This movable latch piece 131 has a slanting detent 137 and a notch 138 at the lower end of said piece serving as a catch for a detent 140 (Figs. 8, 10, 11, 12 and 13) and may be limited in its angular movement by a pin 141 affixed to the lug 133 and passing through a hole 142 in said latch piece. The detent 140 is secured to the lever 115.

In the raised inactive position of the needle carrying head 16 shown in Figs. 8 and 10, the detent 140 will be in raised position opposite and adjacent to the detent follower edge 137 of the latch piece 131 and the solenoid 136 will be de-energized, so that its plunger 135 will be in lowered position and said latch piece will be urged clockwise (Fig. 10) about its pivot support 134 against said detent. The weight of the plunger 135 and of the latch piece 131 is sufficient to maintain said latch piece in this position. However, if desired, the plunger 135 may be spring-loaded.

When the treadle 111 is depressed, the lever 115 is depressed and this causes the detent 140 on said lever to ride along the follower edge 137 on the latch piece 131 and to cam said latch piece counterclockwise (Fig. 10) about its pivot support 134 out of the way until the detent reaches the notch 138. The plunger 135 has limited transverse play in the solenoid coils to permit this camming of the latch piece 131 out of the way of the descending detent 140. When the detent 140 reaches the notch 138, the latch piece 131 snaps clockwise about its pivot support 134, while the detent 140 continues to move downwardly with the lever 115 until said detent reaches the limit of its lowermost position, as shown in Fig. 11, determined by the engagement of said lever with an adjustable stop screw 142 (Fig. 8) threaded into the bracket 24. In this limiting position, the detent 140 is a small distance below the stop end of the notch 138 and the fabric on the bed-plate 13 is under maximum pressure from the spring-biased presser foot 45. This starts the heat stretching of the penetrated loops or stitches of the fabric being marked. When foot pressure is removed from the treadle 111, the lever 115 under the action of the spring 124 lifts the lever until the detent 140 reaches the stop end of the notch 138 on the latch piece 131, as shown in Fig. 12. In this position, the pressure of the presser foot 45 on the fabric being marked is relieved slightly, but the heated needles 15 continue their heat stretching operation on the fabric.

As soon as the lever 115 is lowered, the heat stretching cycle is initiated and is automatically terminated by the timer 130. The actuation of the timer 130 causes the solenoid 136 to be energized at the end of a predetermined cycle in the manner to be described. This causes the plunger 135 to be raised and the latch piece 131 to be rotated counterclockwise about its pivot support 134, from the position shown in Fig. 12, a small angular distance sufficient to free the detent 140. This causes the lever 115 to rise instantly under the action of the spring 124 and the needle 15 to rise out of the fabric into inactive position.

The timer 130 may be of any suitable construction and has an electric motor 151 (Figs. 14, 15 and 18) of the usual type employed in connection with clocks and timers. Such a motor, for example may be of the general type disclosed in U. S. Patents 1,977,185, 1,977,186, 1,996,375 and 2,049,261. This timer 130 is removably secured to the rear end of the bracket 24 by screws 150 (Fig. 3) and its motor 151 is connected to a source of power through a cord 149 (Figs. 1, 16 and 18) having a plug 152 for connection to an ordinary wall outlet and passing into the apparatus through the base 10 as shown. In the circuit of this motor 151 is a switch 153 (Figs. 3, 4, 8, 10 and 18) secured in fixed position to a bracket 154 mounted on the guide frame 92 and having a spring-pressed contact plunger 155 in the path of the upper edge of the lever 115, so as to be pressed inwardly by said edge in the inactive raised position of said lever. In this inward pressed position, the switch 153 is open and the timer motor 151 is therefore stationary.

The timer 130 includes not only the motor 151 but a spring-actuated switch 157 (Figs. 14, 15 and 18) in the circuit of the solenoid 136 normally maintained open and closed automatically by the operation of the motor when said motor has rotated a predetermined number of revolutions. The timer 130 for that purpose is shown including a control arm 158 having a hub journaled in a frame plate 159 of the timer and connected to an adjusting head 160. A shaft 161 is journaled at one end in the hub of the control arm 158 and is driven from the motor 151 through a pinion 162 meshing with a gear 163 on said shaft. Affixed to this shaft 161 is a cam arm 164 urged clockwise (Fig. 15) against a stop pin 165 on the control arm 158 by means of a spring 166 anchored at one end and secured at its other end to said shaft, around which it is wound. This spring 166 is supplemented by another spring 167 anchored at one end and secured at its other end to the shaft carrying the pinion 162 and wound around said shaft. A pivoted lever 168 lies in the path of rotation of the cam arm 164 and is swung thereby counterclockwise (Fig. 15) about its pivot support into position to close the switch 157, when said arm is rotated by the rotation of the motor 151.

In the operation of the timer 130, when the lever 115 is depressed by application of foot pressure on the treadle 111, the switch 153 in the circuit of the motor 151 is automatically released and thereby closed and this causes the motor to rotate against the action of the springs 166 and 167 and the cam arm 164 to rotate counterclockwise (Fig. 15) through the gears 162 and 163 from its initial angular position determined by its engagement with the stop pin 165 on the control arm 158, until said cam arm 164 reaches the lever 168. The cam arm 164 raises the lever 168 and thereby closes the switch 157 in the circuit of the solenoid 136. This energizes the solenoid 136 and operates the latch piece 131 in position to release the lever 115, so that it rises under the action of the spring 124. This action opens the switch 153 and deenergizes the solenoid 136. It should be noted that the switch 153 is not only in the circuit of the solenoid 136 but also in the circuit of the motor 151, as shown in the wiring diagram of Fig. 18, so that the release and the attendant rise of the lever 115 into engagement with the contact plunger of the switch 153 instantly shuts off the timer motor 151. The motor 151, when shut off, is free to be rotated in reverse direction by

the unwinding action of the springs 166 and 167, so that the cam arm 164 is restored to its initial inactive position shown in Fig. 15 as determined by the position of the control arm 158.

The length of the fabric heating and penetrating cycle depends on the angular position of the control arm 158. This angular position, and consequently the length of the cycle, can be adjusted through the turning of the adjusting head 160.

In Fig. 18 is shown the wiring diagram for the whole electrical system for the apparatus. In this system, the heater 31 is connected across the main lines through the plug and socket connection 105, 106, so that even if the main plug 152 is connected into the wall socket, the heater 31 may be disconnected until the operator is ready for a run. For that purpose, the electric connection 105 (Figs. 5, 8 and 18) is adapted to receive the connection 106 from the main lines coming out of the side of the post 10 or the frame arm 12.

A snap switch 169 (Figs. 3 and 18) across the main lines is mounted on the side wall of the frame column 29 and a signal light 170 in the circuit of said switch and mounted on said column alongside of said switch indicates when said circuit is connected to the main lines.

A connector block 172 (Figs. 10 and 18) serves to connect the wiring from the different electrical units together. This block is shown secured to the bracket 154 affixed to the frame supporting the solenoid 136.

A counter 175 (Figs. 3 and 4) is supported on the upright 29 and has a shaft 176 with an arm 177 attached thereto adapted to be actuated during every marking operation of the apparatus by a pin 178 on a block 156 carried by the lever 115.

The apparatus is constructed to support stockings which are in undyed and unfinished condition in position easily accessible to the operator and to support these stockings after they have been marked in position also easily accessible to the operator. For that purpose, on the rear of the column 20 are two lugs 180 (Figs. 1, 3 and 4) having apertures to receive the pivot ends 182 of two rods or wires 183, each bent to form a holder with a crook 184 over which the loose hosiery is hung. These holders 183 may be swung about the axes of their pivot ends 182 to extend outwardly sideways from the column 20 or forwardly into position accessible to the operator or may be swung rearwardly out of the way. The operator merely picks up the stockings from one holder 183, marks them and then hangs them on the other holder 183.

The table 17 (Figs. 1 and 4) may be employed to support the stockings when they are finished, dyed and stacked as shown in Fig. 1. This table 17 has a pair of long rods 191 extending obliquely thereacross for stability and fixed to said table at one end, as for example by rivetting. At the other end, these rods 191 project beyond the edge of the table 17 and are adapted to be removably fitted in two holes respectively in a split collar 193 clamped to the pillar 18. The position of the collar 193 on the pillar 18 may be changed to change the elevation of the table 17 and this table may be removed when not required.

It may be desired to emphasize the penetrative markings in the stocking by coloring. For that purpose, there is provided on one side of the arm 12 a reel 196 (Figs. 1, 3 and 4) supported for free rotation on a spindle 197 secured to a bracket 198 having a base 200 affixed to the

underside of the bracket 24. Wound on this reel 196 is a paper ribbon 201 containing a suitable transfer dye. This ribbon 201 runs from the reel 196 across the bottom of the presser foot 45 and is punctured by the heated needles 15 during the descent thereof. During this operation, the needles 15 pick up dye from the ribbon and transfer it to the stitches or loops of the stocking being penetrated and stretched by said needles, so that these stitches will be colored.

For guiding the dye ribbon 201 past the presser foot 45 and to locate the end of said ribbon in position easily accessible to the operator for pulling, the presser foot plate 46 (Figs. 5 and 7) has a pair of slits 203 in the ends of said plate projecting beyond the insulating plate 48 and secured to the end of the bracket base 260 on the side of the arm 12 opposite the reel 196 is an upright rod 265 (Figs. 1 and 4) terminating in an elongated eyelet 206. The dye ribbon 201 is threaded through the slits 203 in the presser foot plate 46 and through the eyelet 206 and hangs down at the end as shown in Fig. 5. The operator at the end of each marking operation pulls the dye ribbon 201 at the hanging end thereof, to move a fresh section of said ribbon across the bottom of the presser foot plate 46 for the next marking operation.

In order to prevent the dye from the ribbon 201 from being transferred to and over the surface of the stocking in the region being penetrated, the stocking is shielded against direct contact with said ribbon. For that purpose, there is provided a second reel 210 (Fig. 1) alongside of the reel 196 supported for free rotation on a spindle 211 secured to the bracket 198. Wound on this second reel 210 is a protective paper ribbon 212 colorless or colorably inert and run from said reel in underlying relationship with respect to the dye ribbon 201 through the presser plate slits 204 and through the eyelet 206, so as to be interposed between said dye ribbon and the stocking being marked. The protective ribbon 212 is fed in successive sections with the dye ribbon 201 through the apparatus by pulling the hanging ends of these ribbons together and serves not only to prevent dye transfer to the stocking except through the needles 15, but may also serve to heat insulate the stocking while the presser foot 45 is down in case such presser foot should for some reason become hot from long operations.

In the operation of the apparatus, when the table 17 is set up, and the articles to be marked are dyed, finished stockings, these stockings A neatly stacked are laid on the table, and the stack doubly folded with the upper parts of the stockings overlying the lower foot parts. The upper part of the top stocking of the folded stack, which was originally the bottom stocking of the stack before it was doubly folded, is then slipped over the bed-plate 13, so that the part of this stocking to be marked lies flat over the female die plate 14 on said bed-plate as shown in Figs. 1 and 8. The treadle 111 is then depressed, and this lowers the head 16 carrying the heated needles 15. These needles 15 in their descent puncture the dyed and protective ribbons 201 and 212 and penetrate the loops or stitches in the stockings. At the same time, the switch 153 is released and thereby closed and this causes the timer motor 151 to rotate. The operator releases the foot pressure on the treadle 111, but the head 16 remains in lowered heat stretching position through the operation of the latch device 131, 140,

until the timer 130 shuts off the switch 157 in the circuit of the solenoid 136. This operates the latch device 131, 140 and releases the head 16 for return upward movement.

5 The stocking which has been marked with the desired insignia B is then laid flat full length on to the table 17, and the next folded stocking above it is subjected to the same operation after the next sections of the ribbons 201 and 212 have 10 been pulled into operative position across the presser foot 45. These operations are repeated until the last stocking as shown in Fig. 1 is marked.

What is claimed is:

15 1. In an apparatus for forming a permanent mark of predetermined design in a fabric, the combination of means for supporting a bank of needles arranged in accordance with a predetermined pattern, means under manual control for moving the needle supporting means from inactive position into operative position to cause the needles to penetrate the fabric to be marked, said means comprising a reciprocatory head on which the needle supporting means is mounted and pivoted operating lever connected to said head, a timer, means for automatically initiating the operation of the timer when the needle supporting means is moved into operative position, latch means mounted on a fixed support 20 and engageable with said head operating lever, for automatically holding the needle supporting means when the needle supporting means reaches operative position, solenoid means for releasing the latch means, means responsive to the operation 25 of the timer for a predetermined period for actuating the solenoid means in position to release the latch means and to permit thereby the needle supporting means to return to inactive position, and means for returning the needle supporting means to inactive position upon release of the latch means.

30 2. In an apparatus for forming a permanent mark of predetermined design in a fabric, the combination of means for supporting a bank of needles arranged in accordance with a predetermined pattern, means under manual control for moving the needle supporting means from inactive position into operative position to cause the needles to penetrate the fabric to be marked, said means comprising a reciprocatory head on 35 which the needle supporting means is mounted and a pivoted operating lever connected to said head, a timer having a motor, a switch, and means for closing the switch when the motor has rotated a predetermined number of revolutions, a second switch in the circuit of the motor, means for opening the second switch automatically while the needle supporting means is in inactive position and for closing the second switch automatically when said needle supporting means is 40 moved out of inactive position towards operative position to initiate the rotation of the motor, latch means mounted on a fixed support and engageable with said head operating lever for automatically holding the needle supporting means 45 in operative position, a solenoid in the circuit of the timer switch for releasing the latch means when the solenoid is energized, and spring means for moving the needle supporting means to inactive position when the latch means has been released, the second switch being also in the circuit of the solenoid, whereby the timer motor is stopped and the solenoid is de-energized when the needle supporting means reaches inactive 50 position.

55 3. In an apparatus for forming a permanent mark of predetermined design in a fabric, the combination of means for supporting a bank of needles arranged in accordance with a predetermined pattern, means under manual control for moving the needle supporting means from inactive position into operative position to cause the needles to penetrate the fabric to be marked, said means comprising a reciprocatory head on which the needle supporting means is mounted and a pivoted operating lever connected to said head, a timer having a motor, a switch, and means for closing the switch when the motor has rotated a predetermined number of revolutions, a second switch in the circuit of the motor, means for opening the second switch automatically while the needle supporting means is in inactive position and for closing the second switch automatically when said needle supporting means is moved out of inactive position towards operative position to initiate the rotation of the motor, latch means mounted on a fixed support and engageable with said head operating lever for automatically holding the needle supporting means in operative position, a solenoid in the circuit of the timer switch for releasing the latch means when the solenoid is energized, and spring means for moving the needle supporting means to inactive position when the latch means has been released, the second switch being also in the circuit of the solenoid, whereby the timer motor is stopped and the solenoid is de-energized when the needle supporting means reaches inactive 60 position.

11

3. In an apparatus for forming a permanent mark of predetermined design in a fabric by stretching the stitch loops thereof, the combination of means for supporting the fabric in position for marking, a bank of needles arranged in accordance with said design, means for reciprocating the needles towards the fabric supporting means into fabric penetrating position and away from the fabric supporting means into inactive position, a reel for supporting a supply of color transfer ribbon, and a presser foot resiliently mounted for movement with the needles and for yieldable movement with respect thereto, said presser foot having openings to permit the color transfer ribbon to be threaded across the presser foot between it and the fabric to be marked, whereby the ribbon is punctured by the needles during their movement towards fabric penetrating position and the color from the ribbon is consequently transferred by the needles to the penetrated loops of the fabric, the ribbon threading means permitting the ribbon to be fed lengthwise, whereby successive sections of the ribbon may be brought into puncturing position with respect to the needles.

4. In an apparatus for forming a permanent mark of predetermined design in a fabric by stretching the stitched loops thereof, the combination of means for supporting the fabric in position for marking, a bank of needles arranged in accordance with the said design, means for reciprocating the needles towards the fabric supporting means into fabric penetrating position and away from the fabric supporting means into inactive position, means for supporting a puncturable color transfer sheet in the path of the needles between the needles and the fabric supporting means, whereby the transfer sheet is punctured by the needles during their movement towards fabric penetrating position and the color from the transfer sheet is consequently transferred by the needles to the penetrated loops of the fabric, and means for supporting a protective sheet between the color transfer sheet and the fabric supporting means to prevent transfer of color from said sheet to the fabric except through the needles.

5. In an apparatus for forming a permanent mark of predetermined design in a fabric by stretching the stitch loops thereof, the combina-

12

tion of means for supporting the fabric in position for marking, a bank of needles arranged in accordance with said design, means for reciprocating the needles towards the fabric supporting means into fabric penetrating position and away from the fabric supporting means into inactive position, a reel for a supply of color transfer ribbon, a second reel for a supply of protective ribbon, and means for threading the two ribbons from the reels in overlying relationship across the path of reciprocating movement of the needles with the protective ribbon intervening between the color transfer ribbon and the fabric supporting means, whereby the color transfer ribbon is punctured by the needles during their movement towards fabric penetrating position and the color from the color transfer ribbon is consequently transferred by the needles to the penetrated loops of the fabric, while the fabric is protected against direct contact from the color transfer ribbon by the protective ribbon, the ribbon threading means permitting the two ribbons to be fed together lengthwise, whereby successive sections of the ribbons may be brought into the puncturing field of the needles.
